UNITED STATES PATENT OFFICE.

ALBERTIS C. TAYLOR, OF WARREN, OHIO, ASSIGNOR TO THE WINFIELD MANUFACTURING COMPANY, OF WARREN, OHIO, A CORPORATION.

ELECTRIC RIVETING-MACHINE.

1,261,972.

Specification of Letters Patent. Patented Apr. 9, 1918.

Application filed September 19, 1916. Serial No. 121,026.

To all whom it may concern:

Be it known that I, ALBERTIS C. TAYLOR, a citizen of the United States, residing at Warren, in the county of Trumbull and 5 State of Ohio, have invented certain new and useful Improvements in Electric Riveting-Machines, of which the following is a specification.

In the accompanying drawings, Figure 1 10 is front elevation of the machine, and Fig. 2 is a vertical central sectional elevation thereof front to rear. Fig. 3 is a cross section on line 3—3, Fig. 2.

Fig. 4, Sheet 3, is a side elevation of the 15 upper portion of the machine viewed from the right of Fig. 1 and Fig. 5 is an elevation of the opposite side from Fig. 4 with the fly or band wheel sectioned away and disclosing the clutch mechanism in full lines. Fig. 6 is a sectional plan view on the line 20 6—6, Fig. 5, showing the clutch mechanism in section and engaged. Fig. 7 is a section on line 7—7, Fig. 5, Figs. 8 and 9 are details of the bolt and plunger employed in the 25 clutch mechanism hereinafter described.

The invention herein is a modification of the machine shown in a contemporaneous application filed by me and bearing Ser. No. 121,025, and the difference herein over said 30 application is found in certain details and particularly in the manner of applying the power to complete the riveting operation and incidentally in the hand control of the current and in the means for bringing the 35 electrodes onto the rivet as fully set forth in the accompanying description and claims.

The present structure, like the foregoing, has a cast metal body or frame F upon which the operating parts are mounted and 40 comprises two different lines of mechanism leading up to and adapted to give contact and operating effect to the riveting members a and b. These members, referred to herein as electrodes or dies, since they serve 45 to electrically heat and upset the rivets, are suitably shaped at their ends to engage the head and the point of the rivet, respectively, the lower electrode being substantially stationary and the upper electrode movable 50 vertically within limits to rest down upon

the rivet r, which is first placed in the stock s.

In riveting operation the first step is to bring the electrodes into acting position on the rivet, as seen in Fig. 2, and this brings 55 the rivet into the electric circuit when the same is closed through the transformer t and the electrical connections broadly indicated by 4 which carry the electrodes in their terminals. The upper electrode a is 60 carried by a yoke a' arranged to slide independently upon the head h, and suitable nuts and a screw a² serve to adjust and fix the yoke and electrode in different positions to facilitate operation. Head h is 65 slidably supported in the main frame F having side guides engaging the edge thereof, and a weight w suspended by a cord or cable k and sheaves S and S' serves to overbalance the head and raise the electrode a to promote a safe and easy operation thereof through the hand lever 3, Fig. 4. The said lever is mounted on a pivot shaft 9 in the body F and which shaft carries a toothed 70 segment 16 engaging a rack-bar or rod 10 75 bearing at its lower end against a lug on the rear of head h and slidably vertically in suitable supports in said body, the said rod serving to lower said head and the upper electrode thereon within prescribed limits. 80

In this machine it is necessary to have the counterweight w heavier than the slide h as there is no other means of raising the electrode a. The rack 10 is not attached to the slide but only bears on projections in the 85 rear. If this rack were attached to the slide when the treadle was tripped, the slide h' would travel down and hit slide h and cause the hand lever to come down at a high rate of speed which would be liable to injure the operator. Lever 3 thus becomes the initial actuating member to seat the upper electrode on the rivet, and in the present machine lever 3 also carries an electrical switch, comprising a hand grip 3' pivoted 90 on the extremity of said lever and having a right angled extremity in which a contact c' is mounted. The other contact point c is fixed on or in a right-angled projection 95 on the ends of lever 3, and a fairly stiff 100

compression spring 13 is interposed between said right angled projections and keeps the said contact points normally apart. It follows by this separation of the said contacts and support of grip 3' that the head *h* can be depressed or lowered to rest the upper electrode on the rivet before the said compression spring will yield enough to bring the said contact points together. 5 Then, however, upon the exertion of further down pressure upon said grip 3' the said contacts will be closed and the electric circuit of which they constitute a part will also be closed on the transformer and the rivet 10 will be almost instantly heated to an upsetting temperature without materially heating the electrodes. Then a very little further depression of the lever will upset the rivet more or less completely and leave the 15 work to be absolutely completed by the power mechanism.

To this end I employ the power shaft *m* which has a slight crank 8 with which the coupling rod 7 is suitably connected, and a 20 plunger head *h'* is engaged with said rod and slidably mounted in said guides in head *h*, Fig. 3. The head *h* has a projection or lug 15 at its bottom immediately over electrode *a* upon which the plunger *h'* is adapted 25 to bear on its downward thrust, and the present plan of the machine contemplates a single power stroke through these parts as sufficient to complete the riveting. However, additional strokes can be delivered if 30 required.

Engagement with the power mechanism is effected through a clutch mechanism on shaft *m* and adapted to make operating engagement with the constantly revolving 35 wheel *n*, which is otherwise free to rotate on said shaft, Fig. 6. The hub of said wheel has a recess or hole 34 on its inside, and a collar 35 fixed on shaft *m* carries a bolt 33 adapted to be thrust into said hole 40 or recess by pressure of the spring 41 behind the same when the wheel turns to engaging position, assuming said bolt to be free or released. However, said bolt is held back by means of a spring pressed plunger 39, 45 having a tooth or point engaging in a recess or hole in the side of said bolt, Fig. 6, and the said plunger in turn is held back against the pressure of its own springs 42 by a pivoted 50 detent or dog 38 having a tooth 45 normally engaging in a hole in the side of said plunger, Fig. 7. In this retired and normal position of the said parts the wheel *n* is rotating and shaft *m* is at rest. The detent 38 is pivoted between its ends in a pivoted lever 55 40 and becomes the medium for withdrawing the plunger 39 from bolt 33 when said lever is actuated by the treadle mechanism provided for this purpose and which comprises the treadle 26, links 30 and 32 and le-

ver 31 connecting said links. This frees said 65 bolt for locking engagement with wheel *n*.

After a single revolution of said wheel the bolt is automatically withdrawn first by a cam 36 on collar 35 engaging a beveled lug 37 on the said detent, which is now in engagement with the plunger 39 and carries it back against its springs 42 and disengages bolt 33. Then as said bolt is carried around a short distance by the wheel the beveled shoulder 48 thereon engages the beveled 75 surface 46 on the plunger and the bolt is withdrawn from the wheel and pressed back far enough to be again engaged by the plunger and locked in retirement. As to this mechanism and operation it may be said 80 that the same is shown and claimed in the application above referred to and therefore is not claimed herein.

The lever 3 has a counterweight *w'* connected therewith to promote easy operation, 85 and said lever is operated exclusively by the pivoted and spring pressed hand grip 3' thereon.

Spring 49 serves to hold the treadle 26 in position to be depressed to liberate the 90 clutch mechanism as described, and the lower electrode is supported by the pivoted member 50 having a rubber bumper 51 to relieve excessive strain that may come onto the said electrode and work.

Yoke *a'* provides an adjustable holder for the upper electrode *a* and a terminal for the flexible, laminated transformer bands 4, while head *h* is a carrier for said parts which is operably dependent upon power 100 applied through three sources, to wit:—the rack bar 10 which serves as a presser member, the slide *h'* which operates as a striker or hammer, and the weight *W* or its equivalent which causes an uplift of the head and 105 affords an elastic or yielding connection adapted to maintain working relations between the independently movable parts.

What I claim is:

1. In a machine as described, a pair of 110 electrodes, a movable head carrying one of said electrodes and means to actuate said head comprising a rack separably engaged with said head, a weight to hold said head and rack in working relation, and a lever 115 and toothed segment to actuate said rack.

2. A machine as described having a pair of opposed electrodes, and means to raise and lower the upper of said electrode comprising a slidable head and a separate rack 120 slidably mounted to bear down on said head, a hand lever and a toothed segment operated thereby engaging said rack, and a counterweight to maintain said head in bearing engagement with said rack, in combination 125 with a power device to depress said head independently of said rack.

3. A machine as described having a pair

- of alined electrodes and means to raise and lower the upper of said electrodes and to turn the electric current thereon comprising a sliding head carrying the said upper electrode, a rack and a lever and a toothed segment to actuate said head initially, electric contact points mounted on said lever and adapted to close the electric circuit on said electrodes during the initial stages of operation, and power means to operate said head finally and independently of said rack and lever mechanism.
4. The machine described having two electrodes and means to raise and lower the upper electrode initially comprising a lever to actuate said electrode provided with electrical contacts and means on said lever to close said contacts and turn the current on said electrodes, in combination with a slide and power means to actuate said head independently of said lever.
5. The machine described comprising a sliding head and an electrode thereon, a rack fixed on said head, a lever and segment to operate said rack, and an over-balancing weight connected with said head to aid in the operation thereof.
6. The machine described having a pair of electrodes, a head carrying the upper of said electrodes and hand controlled mechanism to lower said head, in combination with a power actuated plunger adapted to bear on said head and depress the same.
7. The machine described having a pair of electrodes and slidably mounted head carrying the upper electrode, in combination with a power actuated plunger slidably mounted upon and adapted to depress said head and a separate device to impart an initial movement to said head independently of said plunger.
8. The machine described, comprising a pair of electrodes and a head carrying the upper electrode, a plunger slidably mounted in respect to said head and adapted to bear thereon and power shaft and crank to actuate said plunger.
9. The machine described, comprising a slidable head and an electrode fixed thereon, in combination with a plunger slidably mounted on said head and adapted to depress the same and a crank shaft and coupling rod operated thereby in actuating relations with said plunger.
10. An electric riveting machine having a slidable head and means to operate the same, and an electrode having a supporting member slidably engaged with said head and means to fix said member and electrode adjustably at different elevations upon said head.
11. An electric riveting machine having a vertically-movable head and a slidable yoke and a screw and nut to fix said yoke ad-
- justably upon the bottom of said head, an electrode carried by said yoke, and means to operate said head.
12. In an electric riveting machine, a set of opposed electrodes, a vertically-movable head for one of said electrodes, a presser member in separable bearing engagement with said head, means to operate said presser member, a hammer in striking engagement with said head, means to operate said hammer, and means to maintain operable engaging relations between said independently movable parts.
13. In an electric riveting machine, a set of electrodes, a vertically-movable tread having a terminal holder for one of said electrodes, a presser member bearing upon said head, a hammer in striking relation with said head above said electrode, a device to produce a constant uplift upon said head, and separate mechanisms to operate said hammer and presser member, respectively.
14. In an electric riveting machine, a set of opposed electrodes, a slidable head carrying one of said electrodes, self-acting means to raise said head, a hammer in striking relation opposite said head, power-operable means to actuate said hammer, a slidable presser bar in bearing engagement with said head, and manually-operable means to actuate said presser bar.
15. In an electric riveting machine, an upper and a lower electrode and movable holders for each, a device to apply pressure on the upper electrode through its holder, self-acting means to raise said upper electrode and its holder, and a movable support for the lower electrode having a yielding backing to accommodate excess pressure upon the work and lower electrode.
16. In an electric riveting machine, an upper and lower electrode and independently movable holders therefor, a yielding bumper for one of said holders and a striking hammer and separate presser member for the other holder, and independent operating means for said hammer and presser member, respectively.
17. In electric riveting machines, a set of electrodes having separate holders, a movable head for one of said holders, a striking hammer and a separate presser member for said head, power applying means for said hammer, a treadle and means connected therewith to control the operation of said power applying means, and a manually-operable device for said presser member, in combination with electrical means to transmit an electric heating current to said electrodes during riveting operations.
18. In an electric riveting machine, a set of electrodes, a slidable head carrying one of said electrodes, a member to depress said

head, a lever to operate said member, an electric switch having a handle mounted upon said lever for joint operation of the switch and lever, an over-balancing weight connected with said head, a hammer in striking relation with said head, a power-applying device for said hammer, clutch mechanism to control the operation of said

device, and a treadle and operating connections for said clutch mechanism.

In testimony whereof I affix my signature in presence of two witnesses.

ALBERTIS C. TAYLOR.
